CENTRIFUGAL SEPARATOR

Frederick H. Smith, Philadelphia, Pa., assignor to
 The Sharples Corporation, a corporation of
 Delaware

Application September 16, 1948, Serial No. 49,605

4 Claims. (Cl. 233—7)

1

This invention relates to centrifugal apparatus adapted for the separation or clarification of mixtures of liquids and solids, and has to do more particularly with an improved continuous type of horizontal centrifuge.

Horizontal centrifuges utilizing a scroll or helical screw to convey the solids in the opposite direction from the liquid flow within the centrifuge are well known. Likewise, centrifuges utilizing a stack of "discs" comprised of a plurality of closely spaced conical members which act as the separating or clarifying element are also well known. The scroll is independently journaled from the rotor or bowl since the scroll rotates at a slightly reduced speed in order to provide the scrolling action.

The scroll type of centrifuge is adapted for relatively large volumes and high percentage of solids whereas the disc type of centrifuge is utilized for its higher clarification efficiency but the conventional disc machine cannot ordinarily be used for continuous operation because of its tendency to plug after comparatively limited periods of use. The above disadvantages are especially critical for certain materials and in certain chemical extraction processes. The solids in the centrifuge frequency are not sufficiently plastic to be ejected through the fine nozzles employed with a disc type centrifuge and as mentioned above the solids are frequently too large in volume to be handled in the disc machine under continuous operation.

Nevertheless, such continuous operation is highly desirable in many chemical processes in order to handle the relatively large quantities of material involved. Furthermore, a disc type of machine is also desirable to obtain satisfactory clarification. Therefore, in order to provide a continuous machine which has the required clarification it is desirable to incorporate an efficient scroll in the disc centrifuge.

The problems involved in providing a satisfactory scroll for a disc centrifuge are not, however, simple of solution. In the first place, the overall diameter of the machine should be kept at a minimum. In the second place, the scroll must have controlled clearance with the side of the bowl but at the same time there must be no scraping between the scroll and the bowl. This condition would of course cause excessive wear. Furthermore, the high stresses involved due to centrifugal force require that a rigid construction be employed which has a minimum of weight but at the same time is strong enough to prevent failure at the relatively high speeds employed with disc centrifuges.

2

A primary object, therefore, of the invention is to provide in horizontal centrifuge construction, a combined disc and scroll rotor assembly.

A still further object is to provide in a machine of this type an improved disc stack.

A still further object is to provide in a machine of this type an improved conveyor body assembly on which both the disc stacks and the scroll may be mounted.

10 A still further object is to provide in a machine of this type a conveyor assembly so fabricated as to have ample radial rigidity and strength to carry the high loads imposed by the centrifugal force of the combined scroll and stacks.

15 A still further object is to provide in a machine of this type a scroll rotating at slight differential speed which is at the same time mounted on the conveyor body rather than independently journaled.

20 A still further object is to provide in a machine of this type means for avoiding plugging of the machine in the event of excess feeding.

Further objects will be apparent from the specification and drawings in which:

25 Fig. 1 is a longitudinal section of a centrifuge constructed in accordance with the invention, as seen at 1—1 of Fig. 2;

Fig. 2 is a transverse section of the structure of Fig. 1 as seen along the line 2—2 of Fig. 1;

30 Fig. 3 is a longitudinal section on a reduced scale of the conveyor body weldment;

Fig. 4 is an enlarged detail of one of the disc stack assemblies;

Fig. 5 is a section taken on the line 5—5 of Fig. 4;

35 Fig. 6 is an end elevation of the structure of Fig. 4; and

Fig. 7 is an exploded perspective on an enlarged scale of one end of the disc stack showing the method of assembly.

40 Referring now more particularly to the drawings, a centrifuge constructed in accordance with the invention has a stationary case 10 which encloses the rotor or bowl 11. The bowl 11 has a slightly tapered cylindrical portion 11a, and a frusto-conical portion 11b; and it will be understood that slurry introduced into the bowl as it is rotating at high speed is separated by the mechanism to be described more fully hereinafter so that the liquid will be withdrawn from the bowl through ports 12, 12, whereas solids will be withdrawn from the bowl through a plurality of ports at the opposite end of the bowl, one of which is shown at 13.

45 50 55 Bowl 11 is rigidly attached at one end to a driving cap 14 which extends through case 10 and

is journaled in bearings (not shown). Driving force for the bowl is supplied through the hollow shaft 14a formed integrally with cap 14. The conveyer body assembly 15 is independently journaled on cap 14 by means of bearing 16 to which it is connected by means of an annular collar 17 and screws 18. Bearing 16 may be lubricated by means of a grease fitting 19 and a conventional grease retainer 20 is provided between the conveyer body 15 and cap 14. It will be understood that conveyer body 15, collar 17 and bearing member 21 rotate at high speed with respect to casing 10 but at the same time have a slightly slower speed than that of bowl 11. Bearing 16 provides for this differential movement between the bowl 11 and the conveyer body 15.

The construction of the opposite end of the machine includes a cap 25 securely bolted to the large end of bowl 11 by means of screws 26, 26. Cap 25, in a manner similar to cap 14, is formed integrally with a driving sleeve 25a which is mounted rotatably on a shaft 26 in order to provide the differential speed between the bowl 11 and the conveyer body 15. Shaft 26 extends within the conveyer body 15 and is splined to an annular thrust collar 27 which encloses thrust bearing 28. Collar 27 is secured to bearing member 29 and conveyer body sleeve 30 by means of screws 31-31. A suitable gasket 32 and oil seal 33 are likewise provided. It will be understood that the conveyer body is journaled radially on bearings 16 and 28 so that it is free to rotate independently in bowl 11 in accordance with the speed of shaft 26. A standard differential gear unit (not shown) connects sleeve 25a and shaft 26 so that driving force exerted on sleeve 25a through bowl 11 and sleeve 14a serves to drive conveyer body 15 in the same direction but at a speed of substantially 20-25 R. P. M. less.

Referring now more particularly to Fig. 3 the conveyer body 15 comprises a weldment which has been very carefully constructed to withstand the extremely high radial stress imposed upon this assembly. It has been found highly desirable to incorporate the portion 40a of scroll 40 around the periphery of the conveyer body rather than to have it independently mounted. Otherwise the necessary scroll framework would seriously hamper the free passage of solids, and furthermore, it would occupy so much space that the over-all diameter of the machine would be greatly increased with concurrent increase in cost without any proportional gain in clarification. In the present machine the normal operating speed of the bowl is on the order of 3250 R. P. M. and the normal operating speed of the conveyer body is 3230 R. P. M.

The main conveyer body sleeve 41 is reamed at one end as shown at 42 in Fig. 3 to accept the sleeve 30. An annular ring 43 is welded around the same extremity of sleeve 41 and this ring is drilled and tapped at 44 to accommodate screws 45 (Fig. 1) which retain the sleeve 30 in sleeve 41. The opposite end of sleeve 41 has a cap 46 welded thereto and provided with radial milled slots 47 through which gusset plates 48 may be welded to the cap. The gusset plates 48 are also welded to the bore of sleeve 41 to provide ample strength and rigidity. A plurality of fins 49 (in the present example 12) are then radially welded along their edges to the periphery of sleeve 41 so that the fins, when in place, substantially extend axially the length of sleeve 41.

The outer edge of each fin is provided with a crossbar 49a which is attached to the fin by

means of welding through drilled holes 50, 50 in the crossbars. The purpose of this construction is to avoid any weld in the angle formed between the crossbars and the lateral faces of the fins 49; and at the same time to provide ample tensile strength between the crossbar and each fin. The section 40a of double pitch scroll 40 is then securely welded around the outside of each crossbar as shown in Figs. 1-3. This construction is extremely rugged and utilizes both the scroll 40a as well as the radial fins 49 as integral stress members thereby providing ample strength for the relatively concentrated mass around the periphery of conveyer body 15. Since it is essential that the disc stacks 51, 51 must be in spaced relation to sleeve 41 as well as to scroll 40 in order to provide proper passage for the solids and liquids, a substantial mass around the periphery of the conveyer body cannot be avoided without loss of efficiency.

A second sleeve 52 is axially welded to cap 46 and similarly has a reamed bore 53 to accommodate the collar 17. Scroll 40b, likewise of double pitch, is welded around the outer periphery of sleeve 52 and is adapted to form a continuous conveying device together with scroll 40a for solids inside the bowl 11. A plurality of radial feed passages 54 are welded to the outer side of cap 46 as shown in Figs. 2 and 3 and these passages terminate centrally in a circular feed chamber 55 having an axial opening 56. A four-bladed accelerator is positioned in alignment with passages 54 and serves to bring the liquid slurry up to speed in a short time.

Referring now more particularly to Figs. 4-7, the individual disc stacks 51 comprise a pair of side members 60, 60' having biased milled slots 61 on opposite faces of each member. The side members 60, 60' are desirably formed of a synthetic plastic material of relatively light weight. The discs 62, 62 are light weight stampings preferably of aluminum or stainless steel and have oppositely biased edges 62a and 62b. The discs 62 are also tapered so that when the stacks 51 are assembled as shown in Fig. 4, side members 60, 60' will be parallel to a radius of the conveyer body 15. In this way the assembled stacks may be supported between the fins 49 as shown in Fig. 2. In assembling the stacks 51, the discs 62 are inserted in the milled slots 61, 61 whereupon the side members are attached to each other by means of pins 63, 63 (Fig. 7). In the present instance there are twelve of these individual disc stack assemblies.

The stacks 51 are adapted to be slidably mounted between fins 49 and are retained therein by means of clips 64 and screws 65 (Fig. 1). Ample clearance between the inner edge of the stacks and the periphery of sleeve 41 is provided for free passage of liquid as shown clearly in Fig. 2. The stacks are securely held in the conveyer body assembly by means of the crossbars 49a and the radial taper of the lateral faces of the fins 49, 49.

In operation the liquid slurry is fed to the centrifuge through a stationary tube 70 which terminates within feed chamber 55 (Fig. 1). The slurry is then accelerated within chamber 55 by means of accelerator 57 and thrown radially through passages 54, 54. The coarser particles of solids are collected by scroll 40b and removed directly to the right in Fig. 1. When the solids come in registry with port 13 they are thrown radially therethrough by centrifugal force and collected by means of a hopper (not shown) in

the bottom of case 10. Solids which are thrown upwardly impinge on an impeller cover 71 which extends around the upper half of impeller 72. A secondary scroll 73 serves to scrape away any solids which may adhere to cover 71 thus permitting them to fall into the hopper.

Returning now to the slurry which is fed into the bowl from passages 54 the partially clarified mixture enters the interstices between the discs 62 in each disc stack 51, whereupon further clarification takes place. The finer particles of solids slide radially outward along discs 62, and the liquid effluent emerges from the inner edge of the disc stacks into the axial passages 75. These further separated fine particles are collected from the inner bowl face by means of scroll 49a and are scraped gradually to the right in Fig. 1 until they are collected by scroll 49b and discharged from the centrifuge as described above. The effluent in passages 75 discharges from the bowl through passages 12, 12 whereupon it may be collected in any suitable manner. The construction and arrangement of the disc stacks is designed to facilitate cleaning, it will be understood that these stacks may be readily removed for this purpose by means of clips 64 and screws 65.

In the event that the operator feeds quantities of slurry to the machine in excess of that which may be accommodated through passages 54, such excess will back-up and be discharged through the bore 56 of chamber 55 which bore is of greater diameter than the outside diameter of feed tube 70. This excess slurry will then be fed into the clarification zone by means of radial ports 76 in sleeve 52. In the event that port 76 cannot accommodate the excess slurry it will then back-up around the outside of feed tube 70 and be discharged from the machine through the sleeve 77 which extends into the conveyor body and is securely attached to collar 18 so that there is no danger of slurry reaching bearing 16.

This feature of the construction is important to avoid danger or injury in the event that excess material is fed. In view of the fact that the present centrifuge is intended for large quantities of material in continuous operation the possibility of excess feeding is more likely than in a batch type machine.

Another important feature of the construction resides in the double taper provided for bowl 11. Portion 11a of the bowl is provided with a 1° taper to cooperate properly with the discs and the clarifying section of the centrifuge. Portion 11b of the bowl is desirably provided with a 20° taper to provide efficient removal of the coarser solids. This feature reduces the drying path for the solids considerably.

I have therefore provided a comparatively large volume centrifuge which is adapted to handle a mixture having excess solids in such a way that excellent clarification is provided together with extreme dryness of the separated solids. Heretofore, such results could only be achieved by means of a plurality of centrifuges each designed for one of the above results. In

addition, my improved centrifuge operates efficiently whether the solid contents of the mixture to be treated are of a crystalline, fibrous or granular material.

5 I claim:

1. A conveyer body weldment for centrifuges comprising a hollow cylindrical body, a cap welded to one end of said cylindrical body, a plurality of radially extending fins welded to the periphery of said cylindrical body, said fins extending axially of the body, a crossbar welded to the outer lateral edge of each fin, a plurality of removable discs supported between said fins, and a helical scroll welded to the crossbars and enclosing the body, fins, and crossbars.

2. Apparatus in accordance with claim 1 in which the cap has a hollow feed chamber extending coaxially therewith, a plurality of radially extending feed passages in communication with 20 said feed chamber, a cylindrical sleeve coaxially welded to said cap and enclosing said feed chamber, and a helical scroll welded around the periphery of said cylindrical sleeve.

3. Apparatus in accordance with claim 1 in

25 which the cap has a hollow feed chamber extending coaxially therewith, a coaxial opening on an end of said feed chamber, a plurality of radially extending feed passages in communication with said feed chamber, a cylindrical sleeve 30 coaxially welded to said cap and enclosing said feed chamber, a plurality of radial ports in said cylindrical sleeve, a helical scroll welded around the periphery of said cylindrical sleeve, and a stationary feed tube extending axially into the opening of the feed chamber and having clearance between the tube and said opening whereby excess mixture will be discharged from the feed 35 chamber into the cylindrical sleeve and from thence through the ports in said sleeve.

40 4. Apparatus in accordance with claim 1, in
which the cap has a hollow feed chamber ex-
tending coaxially therewith, a plurality of ra-
dially extending feed passages in communication
with said feed chamber, a cylindrical sleeve co-
45 axially welded to said cap and enclosing said feed
chamber, and a tapered helical scroll welded
around the periphery of said cylindrical sleeve.
